CLAIM

The ornamental design for a container for a skin treatment device, as shown and described herein.

DESCRIPTION

FIG. 1 is a perspective view of a container for a skin treatment device configured to be secured to a skin treatment device.

FIG. 2 is a front view of the container for a skin treatment device of FIG. 1.

FIG. 3 is a rear view of the container for a skin treatment device of FIG. 1.

FIG. 4 is a left side view of the container for a skin treatment device of FIG. 1.

FIG. 5 is a right side view of the container for a skin treatment device of FIG. 1.

FIG. 6 is a top view of the container for a skin treatment device of FIG. 1; and,

FIG. 7 is a bottom view of the container for a skin treatment device of FIG. 1.

Features in broken lines are for the purpose of illustrating environmental structure and form no part of the claimed subject matter.

1 Claim, 7 Drawing Sheets
